UNITED STATES PATENT OFFICE

ROBERT L. SARGISSON, OF BERWYN, ILLINOIS, ASSIGNOR TO ASSOCIATED ELECTRIC LABORATORIES, INC., OF CHICAGO, ILLINOIS, A CORPORATION OF DELAWARE

DESIGN FOR A WALL TELEPHONE

Application filed November 2, 1931. Serial No. 41,600. Term of patent 14 years.

To all whom it may concern:

Be it known that I, ROBERT L. SARGISSON, a citizen of the United States of America, residing at Berwyn, Cook County, Illinois, have invented a new, original, and ornamental Design for a Wall Telephone, of which the following is a specification, reference being had to the accompanying drawing, forming a part thereof.

The figure is a perspective view of a wall telephone, showing my new design. The opposite side is like the side shown, while the rear is a substantially plain vertical surface.

I claim:

The ornamental design for a wall telephone as shown and described.

In testimony whereof I have hereunto set my hand this 27th day of October, 1931.

ROBERT L. SARGISSON.
